DESIGN FOR A COMBINED LIGHT AND COVER PLATE FOR ELECTRIC RAZORS

Joseph M. Schumann, Manhattan Beach, Calif.

Application June 8, 1938, Serial No. 77,676

Term of patent 7 years

To all whom it may concern:

Be it known that I, Joseph M. Schumann, a citizen of the United States and a resident of Manhattan Beach, Los Angeles County, California, and whose post office address is 1001 Bayview Drive, have invented a new, original, and ornamental Design for a Combined Light and Cover Plate for Electric Razors, of which the following is a specification, reference being had to the accompanying drawing, forming a part thereof.

Figure 1 on the drawing is a plan view of a combined light and cover plate showing my design;

Figure 2 is a side elevation thereof; and
Figure 3 is a front end elevation.

I claim:

The ornamental design for a combined light and cover plate for electric razors, as shown.

JOSEPH M. SCHUMANN.
